PACKAGE

John S. Cromelin, Chicago, Ill.

Application April 17, 1937, Serial No. 137,405

13 Claims. (Cl. 206—56)

This invention relates to improvements in cigarette packages, and refers specifically to a cigarette package characterized in that it is of convenient form or shape, is relatively rigid and 5 rugged affording protection to the cigarettes contained therein, and is provided with means whereby ready and convenient access to the cigarettes carried in the package may be had.

One of the features of my invention comprises 10 the provision of a package for cigarettes or the like which is light in weight and convenient in shape and yet is characterized by its rigidity and ruggedness.

Another feature of my invention resides in the 15 provision of a package for cigarettes which can be economically produced, both from the standpoint of material, and of the operations involved in the manufacture of the package and the packaging of the cigarettes or other contents.

20 As a most important feature of my invention, means is provided whereby convenient access to the contents of the cigarette package may be gained, permitting the removal of cigarettes one at a time without disturbing the remaining cigarettes in the package or causing them to be displaced as a result of the removal of one or more cigarettes from the package.

Other objects and advantages of my invention 30 will be apparent from the accompanying drawings and following detailed description.

In the drawings, Fig. 1 is a side elevational view, parts being broken away, of my improved cigarette package.

Fig. 2 is a horizontal sectional view taken on 35 line 2—2 of Fig. 1.

Fig. 3 is a vertical sectional view taken on line 3—3 of Fig. 1.

Fig. 4 is an enlarged fragmentary sectional elevational view of a portion of the package illustrated in Figs. 1, 2 and 3.

Fig. 5 is a transverse sectional view taken on line 5—5 of Fig. 4.

Fig. 6 is an enlarged fragmentary top plan view of a portion of the tab-carrying top of the 45 package.

Fig. 7 is a fragmentary transverse sectional view, similar to Fig. 5, of a slight modification of my invention.

Fig. 8 is a perspective view, parts being broken away, of a modified form of my cigarette package.

Fig. 9 is a transverse sectional view of the package shown in Fig. 8.

Fig. 10 is a development of the frame of the 55 package illustrated in Fig. 8.

Fig. 11 is a fragmentary sectional view taken on line 11—11 of Fig. 8.

Fig. 12 is a perspective view of another modification of my invention.

Fig. 13 is a fragmentary sectional view taken 5 on line 13—13 of Fig. 12.

Fig. 14 is a transverse sectional view of the package shown in Fig. 12.

Fig. 15 is an enlarged fragmentary bottom plan view of the lower frame member. 10

Fig. 16 is a sectional view taken on line 16—16 of Fig. 15.

Referring in detail to the drawings, 1 indicates a cigarette package of the type wherein cigarettes 2 are disposed side by side in a single row. The 15 package 1 is adapted to accommodate any desired number of cigarettes, but is preferably constructed to contain twenty cigarettes, the number commonly marketed in packages. By disposing the cigarettes in a single row, the package 20 1 may be made very thin, permitting its accommodation in the breast, side or hip pocket without forming an unsightly bulge; or the same may slip easily into a woman's handbag.

The package 1 comprises essentially a frame or 25 skeleton structure 3 and an outer wrapper 4. The frame 3 is preferably constructed of cardboard or similar relatively heavy material of sufficient caliper to furnish rigidity to the package. I have found that 15 point fibrous board serves 30 admirably for the frame, but I do not wish to be limited to this thickness since the board may be selected, as to thickness, in conformity with rigidity or ruggedness desired. The wrapper 4, on the other hand, serves a different function, 35 namely, that of an envelope or covering and accordingly may comprise a relatively light paper having a desired finish or coating. I have found that an 80 pound "Litho" paper serves ideally, but, of course, my invention contemplates a paper 40 of any weight or finish desired. However, as will be hereinafter more fully described, it is desirable that the wrapper 4, or at least that portion of the wrapper which covers the top of the package, be of short fibre so that it may be easily 45 torn.

The frame 3 is constructed in the form of a relatively narrow unitary strip of material, of an effective width substantially equal to the diameter of the usual cigarette. The strip is folded transversely at spaced intervals along its length to provide a top 5, ends 6 and 7 and a bottom 8, the two ends of the strip terminating at a corner 50 of the package, as indicated at 9 in Fig. 1.

In this form of my invention, the top 5 is of 55

greater width than the members 6, 7 and 8, said top being provided with two integral side flanges 10 and 11, as shown best in Fig. 6, which traverse substantially the entire length of the top. The 5 central portion of the top is provided with a series of L-shaped score lines 12 which define a plurality of tabs 13. The width of the tabs, similar to the width of the ends 6 and 7 and bottom 8, is substantially equal to the diameter of the conventional cigarette.

In assembling my package, the flanges 10 and 11 are folded along the "staffs" of the L-shaped score lines 12 so as to be disposed at right angles to the tabs 13. The remaining frame members 15 are formed by folding the strip along the respective transverse lines to form the corners of the package. These transverse folded lines are so arranged that the length of the ends 6 and 7 is substantially equal to the length of the cigarettes 2 so that the cigarettes can be snugly positioned side by side between the top and bottom. It is preferable that there be, when the package is completely assembled, a very slight pressure at the tops and bottoms of the cigarettes 20 so that relative slipping or displacement of the cigarettes will not take place when one or more cigarettes are removed from the package. The wrapper 4 is then positioned over the cigarettes thus embraced by the frame 3 and is 25 properly folded and sealed to provide an envelope for the cigarettes and frame. The envelope may be sealed by gluing, pasting, cementing or the like or the envelope may be heat sealed. The wrapper is preferably sealed at the ends of 30 the package, but may, if found desirable, be sealed elsewhere on the package.

To gain access to the contents of the package 1, the fingernail may be used to sever the wrapper at the corner 9. It will be noted that the end 40 7 terminates short of the top at this corner leaving a slot 14 unsupported by the frame and only covered by the wrapper. At this point, of course, the wrapper may be easily severed. It will also be noted that the top 5, that is, the endmost tab 13' 45 overhangs the endmost cigarette 2 whereby purchase may be obtained at the edge of the tab 13'. The endmost tab 13' may then be raised, as shown in dotted lines in Fig. 4, the tab being severed along the opposite score-lines 12. Simultaneously, the wrapper embracing the tab 13' is also severed being of easily severable stock. It can readily be seen that when the tab 13' is thus raised, it hinges along the cross-portion of the L-shaped score-lines defining the adjacent tab 13. 50 By exerting a slight lateral pull upon the tab, the same may then be severed from the next adjacent tab exposing the first or endmost cigarette 2. The package may then be tapped or jarred in well known fashion to cause the endmost cigarette, now unconfined at its top, to slip outwardly whereby it may be readily grasped.

Due to manufacturing peculiarities in the making of the cigarette, some cigarettes may be of smaller or larger diameters than others; or 65 some may be packed harder than others and may resist squeezing to a greater degree. To compensate or provide for this irregularity, I purposely form the endmost tab 13' slightly larger than the remaining tabs 13. This normally necessitates making the endmost tab 13'' at the 70 opposite end of the top correspondingly smaller. By this provision, inasmuch as the package will be opened adjacent the tab 13', the removal of any tab in sequence will always expose at least 75 one full cigarette.

In forming the score-lines 12, small ridges 15 protrude from the bottom face of the tabs. Although these ridges are relatively small they function to retain the cigarettes in their proper positions until their respective confining tabs are raised. This, of course, prevents the unused cigarettes from slipping or tilting within the package.

As shown best in Figs. 15 and 16 the bottom 8 may be provided with spaced indentations 15' 10 which may be stamped in the lower face of the bottom thereby providing projections 16' upon the upper face of the bottom member. It is preferable that the projections be relatively small so as not to impair the strength of the bottom member and also that in section said projections be formed ratchet-fashion, with the long tapered side toward the end of the package which is to be opened. It can readily be seen that by the provision of the projections 16' the unused cigarettes 15 will be prevented from shifting when one or more cigarettes are removed from the package.

My cigarette package constructed as hereinbefore described is of light weight, convenient shape and extremely rugged. The construction of the 25 package is such that, in spite of the sparing use of heavy material, it is exceptionally rigid. The rigidity is obtained primarily through the assistance of the envelope or wrapper which, when the package is twisted or subjected to torsion, is 30 immediately placed in tension, thus resisting any efforts which may tend to distort or displace the frame from its normal position. In addition, by the provision of the side flanges 10 and 11, the top is reinforced against stresses which tend to 35 compress the cigarettes endwise.

In a slightly modified form of my package, the flanges 10 and 11 may be formed separate from the tab-carrying top. Such a construction is illustrated in transverse section in Fig. 7 where- 40 in 10a and 11a comprise the separate side flanges. In this construction it is unnecessary to provide the "staffs" or longitudinal score-lines and only cross score-lines are provided on the top 13a. The remaining construction is similar to that de- 45 scribed in conjunction with the package 1.

Of course, one of the important features of my invention resides in the scored or perforated top whereby tabs may be torn off one by one to expose and gain access to the cigarettes. To 50 avoid difficulty in severing the tabs, it will be noted in both constructions hereinbefore described, the tabs may be torn from a body (the remaining portion of the top and the side flanges) which is reinforced to resist the tearing 55 stresses. In other words, by the provision of the side flanges 10 and 11, or 10a and 11a which may be adhesively united to the envelope or wrapper, an upward pull on one of the tabs immediately sets the side walls of the wrapper in tension and provides an anchorage against which the pull may be exerted. In this manner the tearing of one tab will not tend to be entirely resisted by the next adjacent tab.

Referring particularly to Figs. 8, 9, 10 and 11, 65 another modification of my invention is illustrated. In this form of my invention a frame 16 and a wrapper 17 is used. The frame 16 is constructed of a material similar to the frame 3 and the wrapper 17 may comprise the same 70 material as that comprising wrapper 4.

Frame 16 comprises a strip of cardboard or the like which is cut to provide a plurality of spaced notches 17. The strip is adapted to be folded longitudinally along the lines 18 and 19 to divide 75

the strip into three sections, namely, side flanges 20 and 21 and a central section 22. The strip is also transversely folded along the spaced lines 23, 24 and 25 to divide the strip into ends 26 and 27, bottom 28 and top 29. To facilitate the folding of the strip 16, the material comprising said strip may be scored along the lines 18 and 19, and lines 23, 24 and 25.

To assemble the package, the strip 16 is folded along the lines 18 and 19 so as to dispose the side flanges at right-angles to the central section 22. Cigarettes 30 may be positioned in a row with their bottom ends resting upon the central section 22 of the bottom 28, the lower sides of the cigarettes being embraced by the side flanges 20 and 21 of the bottom. The strip may then be folded along lines 23, 24 and 25 to dispose the respective frame members at right-angles to each other, the side flanges overlapping each other in progressive fashion around the periphery of the frame. The wrapper 17 is then applied to the frame in the manner hereinbefore described in conjunction with package 1.

Similar to package 1, the top 29 is scored or perforated to provide a plurality of removable tabs 31, and the endmost tab 31' at one end is larger than the remaining tabs 31, the endmost tab 31' at the opposite end being smaller than the tabs 31. Similar to package 1, the tab 31' overhangs the endmost cigarette 30 and the end of the frame member 27 is spaced from the top, as shown at 32 in Fig. 8, whereby the wrapper 17 may be readily punctured to lift the first tab 31'.

It can readily be seen that, in essence, the package illustrated in Figs. 8, 9, 10 and 11 is similar to the package 1 except that side flanges are provided for each frame member. Otherwise, the function of all the corresponding parts is the same as in package 1. Of course, by the provision of the side flanges 20 and 21, a stronger package can be constructed, or for the same strength, lighter weight materials may be used.

Referring particularly to Figs. 12, 13 and 14, another modification of my invention is shown, wherein 32 indicates my modified cigarette package. In this form of my invention, the skeleton frames of the forms hereinbefore described are supplanted by a substantially completely enclosed inner box 33 constructed entirely of the heavier board hereinbefore described in conjunction with the frames 3 and 16. The box 33 comprises two end walls 34 (one only of which is illustrated), a bottom wall 35, top wall 36, and side walls 37 and 38, all formed from a single blank and appropriately scored and folded to dispose the various walls at right-angles to each other. A wrapper 39 similar to wrapper 4 and 17 embraces the box 33 after cigarettes 40 have been packed therein in side by side relation.

In this form of my invention the top wall 36 is provided with appropriately spaced L-shaped perforations 41, similar to the scores 12, in order to form the separable tabs 42. Provision for the convenient puncturing of the wrapper is also made at the corner 43, the same relationship existing between the top wall 36 and the end wall 34 as hereinbefore described in conjunction with the skeleton form of frame.

Of course, by the provision of the separable tabs 42 comprising the top wall 36 convenient access may be gained to the contents of the package 32 and in this respect all forms of my invention are similar. However, a more rigid, rugged

and durable package can be made in using the inner box 33.

It is to be understood, of course, that I do not wish to be limited to the specific type of materials used, since my invention is operative when used with a wide variety of materials. Further, my package may be used for commodities other than cigarettes; for instance, my package may be used for cigars, small or full size, stick candy or the like. In addition, although I have described my wrappers as comprising a unitary sheet, the use of one or more sheets is contemplated. For example, a long-fibre paper or a paper high in tensile strength, may be used to cover the sides, ends and bottom of the package, whereas a short-fibre or easily tearable material may cover the top as is clearly shown in the sections illustrated in Figs. 5 and 7. In this connection, transparent "Cellophane" or the like may be used to cover the sides, ends and bottom and an easily tearable sheet material may cover the top. The advantages of a package having transparent walls, as is the case where my skeleton frame construction is used with "Cellophane", of course, are obvious. Consequently, I do not wish to be limited as to size, materials, or product to be packaged except as necessitated by the prior art.

Although the projections 16' are not shown in all of my modifications, it is to be understood that they may be formed, if desired, upon the lower frame member.

I claim as my invention:

1. A package for cigarettes which comprises a frame constructed of relatively rigid material embracing a plurality of cigarettes disposed side by side in a single row, a wrapper of relatively flexible sheet material enveloping said frame and cigarettes, the portion of the frame adjacent one end of said cigarettes being scored to define a plurality of separable tabs corresponding in number to the number of cigarettes confined.

2. A package for cigarettes which comprises a frame constructed of relatively rigid material embracing a plurality of cigarettes disposed side by side in a single row, a wrapper of relatively flexible sheet material enveloping said frame and cigarettes, the portion of the frame adjacent one end of said cigarettes being scored to define a plurality of separable tabs corresponding in number to the number of cigarettes confined, and substantially corresponding in position with the ends of the respective cigarettes.

3. A package for cigarettes comprising a strip of relatively rigid material folded to form a substantially close rectangular frame, said frame being adapted to embrace a plurality of cigarettes disposed side by side in a single row within said frame, a wrapper of relatively flexible sheet material enveloping said frame and cigarettes, the portion of said frame adjacent one end of said cigarettes being scored to define a plurality of separable tabs corresponding in number to the number of cigarettes.

4. A package for cigarettes comprising a strip of relatively rigid material of width substantially equal to the diameter of a cigarette folded to form a substantially close rectangular frame, said frame being adapted to embrace a plurality of cigarettes disposed side by side in a single row within said frame, a wrapper of relatively flexible sheet material enveloping said frame and cigarettes, the portion of said frame adjacent one end of said cigarettes being scored to define a plurality of separable tabs corresponding in number to the number of cigarettes.

5. A package for cigarettes comprising a strip of relatively rigid material folded to form the top, bottom and both ends of a substantially closed rectangular frame, said frame being adapted to 5
5 embrace a plurality of cigarettes disposed side by side parallel to the ends of the frame in a single row within said frame, a wrapper of relatively flexible sheet material enveloping said frame and cigarettes, the top of said frame being scored to 10
10 define a plurality of separable tabs corresponding in number to the number of cigarettes, and side flanges constructed of material similar to that comprising the frame disposed adjacent and coextensive with the top of the frame, said side flanges also being enveloped by the wrapper. 15
15
6. A package for cigarettes comprising a strip of relatively rigid material folded to form the top, bottom and both ends of a substantially closed rectangular frame, said frame being adapt- 20
20 ed to embrace a plurality of cigarettes disposed side by side parallel to the ends of the frame in a single row within said frame, a wrapper of relatively flexible sheet material enveloping said frame and cigarettes, the top of said frame being 25
25 scored to define a plurality of separable tabs corresponding in number to the number of cigarettes, and side flanges formed integral with the top frame member and coextensive therewith folded on each side of said top frame member, said side 30
30 flanges also being enveloped by the wrapper. 35
7. A package for cigarettes comprising a strip of relatively rigid material folded to form the top, bottom and both ends of a substantially closed rectangular frame, said strip being folded 35
35 longitudinally to form side flanges on each side of said top, bottom and ends, said frame being adapted to embrace a plurality of cigarettes disposed side by side parallel to the ends of the frame in a single row within said frame, a wrap- 40
40 per of relatively flexible sheet material enveloping said frame and cigarettes, the top of said frame being scored to define a plurality of separable tabs corresponding in number to the number of cigarettes, and side flanges constructed of material similar to that comprising the frame 45
45 disposed adjacent and coextensive with the top of the frame, said side flanges also being enveloped by the wrapper. 50
8. A package for cigarettes comprising an inner member constructed of relatively rigid material defining a box-like body, said body being adapted to carry a plurality of cigarettes side by side in contiguous relationship in a single row, an outer member comprising a wrapper of relatively flexible sheet material enveloping said body, the portion of said body adjacent one end of said cigarettes being scored to define a plurality of separable tabs corresponding in number with the number of cigarettes carried by said body, and substantially corresponding in position with the ends of the respective cigarettes, the endmost tab at one end being larger than the remaining tabs. 55
55
9. A package for cigarettes comprising an inner member constructed of relatively rigid material defining a box-like body, said body being 60
60
- adapted to carry a plurality of cigarettes side by side in contiguous relationship in a single row, an outer member comprising a wrapper of relatively flexible sheet material enveloping said body, the portion of said body adjacent one end of said cigarettes being scored to define a plurality of separable tabs corresponding in number with the number of cigarettes carried by said body and substantially corresponding in position with the ends of the respective cigarettes, the endmost tab at one end being larger than the remaining tabs. 65
65
10. A package for cigarettes which comprises a frame constructed of relatively rigid material embracing a plurality of cigarettes disposed side by side in a single row, a wrapper of relatively flexible sheet material enveloping said frame and cigarettes, the portion of the frame adjacent one end of said cigarettes being scored to define a plurality of separable tabs corresponding in number to the number of cigarettes confined, and substantially corresponding in position with the ends of the respective cigarettes, the endmost tab at one end being larger than the remaining tabs. 70
70
11. A package for cigarettes which comprises a frame constructed of relatively rigid material embracing a plurality of cigarettes disposed side by side in a single row, a wrapper of relatively flexible sheet material enveloping said frame and cigarettes, the portion of the frame adjacent one end of said cigarettes being scored to define a plurality of separable tabs corresponding in number to the number of cigarettes confined, and substantially corresponding in position with the ends of the respective cigarettes, the endmost tab at one end being larger than the remaining tabs. 75
75
12. A package for cigarettes which comprises a frame construction of relatively rigid material embracing a plurality of cigarettes disposed side by side in a single row, a wrapper of relatively flexible sheet material enveloping said frame and cigarettes, the portion of the frame adjacent one end of said cigarettes being scored to define a plurality of separable tabs corresponding in number to the number of cigarettes confined, said tabs having means extending inwardly into the tobacco of the cigarettes. 80
80
13. A package for cigarettes which comprises a frame construction of relatively rigid material embracing a plurality of cigarettes disposed side by side in a single row, a wrapper of relatively flexible sheet material enveloping said frame and cigarettes, the portion of the frame adjacent one end of said cigarettes being scored to define a plurality of separable tabs corresponding in number to the number of cigarettes confined, said tabs having means extending inwardly into the tobacco of the cigarettes, and means at the bottom of said package extending inwardly into the tobacco of the cigarettes to maintain said cigarettes in fixed position within said package. 85
